CALIFORNIA.

PROCESS OF DEHYDRATING OIL.

1,158,253.

Specification of Letters Patent. Patented Oct. 26, 1915.

Application filed June 26, 1915. Serial No. 36,514.

To all whom it may concern:

Be it known that we, FRED W. MCNEAR and PHILIP E. BOWLES, Jr., citizens of the United States, residing, respectively, at Menlo Park, in the county of San Mateo and State of California, and at Reward, in the county of Kern and State of California, have invented new and useful Improvements in Processes of Dehydrating Oil, of which 10 the following is a specification.

The object of the present invention is to provide an improved process of separating water and oil from emulsions thereof, especially those which come from oil wells.

15 In the accompanying drawing, the figure is a vertical sectional view of an apparatus for practising our improved process, certain parts being shown in side elevation.

Referring to the drawing, 1 indicates the 20 metallic wall of a separating chamber, preferably cylindrical, and having an open top 2 and bottom 3. Secured to and extending inwardly from said wall 1 are a vertical series of annular metallic disks 4. Extending centrally through said chamber is a vertical metallic rod 6, the upper and lower ends of which are received in insulators 7, 8, the lower insulator 7 being supported in the bottom of the separating chamber, and the 25 upper tube extending through the top of said chamber and being supported by a spider 5. Secured to said rod are metallic disks 9, each disk 9 extending between, and equidistant from, a pair of adjacent disks 4. 30 A supply pipe 10 conducts the emulsion into the top of the separating chamber, and from the bottom of said separator a pipe 11 leads to a mediate portion of a vertical side of a settling tank 12, from the bottom of which 35 a pipe 13 leads upwardly to a level higher than the entrance of the pipe 11 into the settling tank, while a pipe 14 leads from a point near the top of said settling tank.

40 16 indicates an alternating current generator, the poles of which are connected by wires 17, 18 with the rod 6 and wall 1 of the separating chamber. A rheostat 19, voltmeter 21, ammeter 22 and switch 23 are provided in the circuit. The generator and the 45 50 resistance of the rheostat are such that

there is a difference of potential between the rod 19 and the wall 1 of approximately 6,600 volts, this voltage being desirable when the distance between the disks 4 and the disk 9 is five inches. Valves 24, 26, 27, 28 are 55 provided in the pipes 10, 11, 13 and 14 respectively.

In the preferred way of practising our improved process, the emulsion flows continuously through the separating chamber, and 60 out by the pipe 11 into the settling tank, where the water settles from the oil, and flows out by the pipe 13, while the oil flows out by the pipe 14. The emulsion may also be treated while at rest in the separating 65 chamber, the valve 26 being first closed. After treatment, this valve is opened and the mixture is allowed to flow into the settling chamber.

With each alternation of the electric current, lines of electro-motive force diverge 70 from each edge of the electrodes alternately toward the opposite electrodes. These lines of electro-motive force produce polarization of the intervening minute water globules, so 75 that they tend to approach each other, and the oil intervening between said globules thus becomes thinner. The resistance of the intervening oil being very great, as compared with the resistance of the water globules, the electric current, which flows along the paths of least resistance, flows where the intervening walls of oil are the thinnest, thus increasing the polarization of the globules along said path of least resistance, 80 which still further reduces said resistance, so that the current of electricity is concentrated along that path in an accelerating 85 ratio. The intervening walls of oil become so thin that the electro-motive force finally 90 disrupts one or more of said walls, and, when this takes place, so that the resistance is still further reduced, the current of electricity flowing along said path increases very rapidly until the whole series of walls along 95 the path of least resistance has been broken down. The resistance of said path has now been reduced to so much lower than that by other paths between the electrodes that a very large current flows through said path, 100

with the immediate evolution of heat sufficient to convert some or all of the water in said path of least resistance into steam, which, being a non-conductor, immediately 5 breaks the short circuit along said path between the electrodes, and electric current is then diverted to other paths of low resistance. The intervening walls of oil between the water globules having been broken down, 10 and some or all of the water in the path of least resistance having been converted into steam, the water in said path is now free from admixture with the oil, and will condense in a comparatively large globule and 15 sink through the emulsion.

It is to be remembered that the above-described process takes place very rapidly in successive paths between the electrodes, so that continual evolution and condensation 20 of steam takes place.

During the above process a billowing or wavy motion is observed upon the surface of the liquid and occasionally bubbles of steam as large as one-half of an inch in diameter rise to the surface and escape thereat. The ammeter varies extremely in its reading, the pointer in fact moving instantaneously from almost zero to beyond the extreme 25 range (60 amperes) of the indicator, showing that, just before the conversion of the water into steam, an extremely large current flows between short-circuited electrodes. In an observed case, the temperature of the emulsion before treatment was 156°, and 30 after separation, that of the oil, about 70% of the emulsion, was 151° and of the water 162°, showing that, of the energy of the electric current, very little was converted into heat by electrical resistance, but that most 35 of the energy was absorbed in generating heat to create steam which heat was afterward given up, in a sensible form, to the water.

We are aware that Patents Nos. 987,115, 45 987,116 and 987,117 have been issued to F. G. Cottrell and J. B. Speed and A. C. Wright respectively for inventions, the object of which was to separate oil and water from an emulsion of the same by an alternating 50 current of high potential, and we have put said inventions into practice, so far as they could be used. We have found that the inventions described in Patents Nos. 987,115 and 987,116, in which the electrodes were 55 both stationary, were absolutely ineffectual, no useful results whatsoever being obtained therefrom. The invention disclosed in Patent No. 987,117, in which one of the electrodes was caused to revolve within the other electrode, gave results which were useful, but much inferior to those obtained by our 60 invention. With an apparatus of about one-half the size of one constructed in accordance with Patent No. 987,117, the emulsion can 65 be dehydrated twice as rapidly, with a cur-

rent of only 6,600 volts instead of 10,000 volts, and with far greater efficiency, since in the former case it was impossible to reduce the amount of water in the emulsion to less than 2%, except by reducing the flow of 70 emulsion, whereas with the present process the amount of water can be reduced to one-half of 1%. This feature indicates about 100% greater efficiency, because the difficulty of extracting the water from the emulsion 75 increases in an accelerating ratio as the work progresses. Said patentees relied upon the electro-motive force only to break down the oil partitions between the water globules, and took especial pains to prevent short circuiting between the electrodes, and indeed 80 their inventions consisted wholly in the prevention of short circuiting. We have discovered that far better results are obtained by relying, not upon electro-motive force, 85 but upon heat as an agency to produce coalescence between the water globules, this heat being produced by the passage of the very large electric current which is produced by short circuiting, the amount of heat being 90 such as to convert water globules in the path of the current into steam and by said conversion breaking the electric current in said path.

As showing the difference between our improved process and those above referred to it may be stated that the Cottrell apparatus is very susceptible to a change of temperature, the apparatus being so affected by a change of temperature of ten degrees, that it 95 will no longer work properly. Our process will continue to operate successfully at any ordinary temperatures. Furthermore, in using the Cottrell apparatus of Patent No. 987,117 it is necessary to first fill the separating chamber with clean oil, freed from admixture with water, and to then introduce the emulsion gradually. If the Cottrell apparatus is started on an emulsion, the result will be that so great a load will be placed upon 100 the generator that the safety devices, such as fuses, will be destroyed. On the other hand, our separating chamber can be filled with emulsion, or as it is termed, green oil, and work can be commenced immediately thereon. 110

We claim:—

1. The process of separating oil and water from an emulsion of the same which consists in passing in the same path there-through an alternating current of sufficiently high potential and for a sufficient length of time to completely short circuit the electrodes by means of water globules and generate steam by the heat produced by said 120 short circuiting.

2. The process of separating oil and water from an emulsion of the same which consists in passing through the body of the emulsion an alternating electric current of sufficient 125

duration and sufficiently high potential to first form a chain of water globules across said emulsion, then completely short circuit the electrodes by means of said chain, then 5 generate steam and thereby prevent the passage of the alternating current across said emulsion in the path formed by said chain, and thereby increase the amount of current across said emulsion at other paths therein 10 to form and break complete chains at said other paths in succession in like manner.

In testimony whereof we have hereunto

set our hands in the presence of two subscribing witnesses.
